UNITED STATES PATENT OFFICE.

ANTON OHNEMUS, OF QUINCY, ILLINOIS, ASSIGNOR TO THE EXCELSIOR STOVE AND MANUFACTURING COMPANY, OF SAME PLACE.

DESIGN FOR A STOVE.

SPECIFICATION forming part of Design No. 33,759, dated December 18, 1900.

Application filed November 24, 1900. Serial No. 37,689. Term of patent 7 years.

To all whom it may concern:

Be it known that I, ANTON OHNEMUS, a citizen of the United States, residing in Quincy, in the county of Adams and State of Illinois, have invented and produced a certain new and original Design for a Stove, of which the following is a full, clear, and exact description, reference being had to the accompanying drawing, forming part of this specification.

• The drawing is a perspective view showing my design.

As shown in the drawing, the leading or material feature of my design consists of a cylindrical body having a front decorated

with scrolls and above which is a plain rim 15 surmounted by a scroll-decorated top. Beneath the body is a scroll-decorated enlargement, beneath which is a plain portion, and beneath the plain portion is a scroll-decorated base supported by scroll-decorated legs. 20

I claim as my invention—

The design for a stove herein shown and described.

ANTON OHNEMUS.
